Primary Examiner — T. Chase Nelson

CLAIM

The ornamental design for a shoe bottom, as shown and described.

DESCRIPTION

FIG. 1 is a perspective view of a shoe bottom according to the present invention;

FIG. 2 is a bottom view of the shoe bottom of FIG. 1;

FIG. 3 is a top view of the shoe bottom of FIG. 1;

FIG. 4 is a right side view of the shoe bottom of FIG. 1;

FIG. 5 is a left side view of the shoe bottom of FIG. 1;

FIG. 6 is a front view of the shoe bottom of FIG. 1; and,

FIG. 7 is a rear view of the shoe bottom of FIG. 1.

The broken line illustration of environmental structure in the drawings is not part of the claimed design.

1 Claim, 7 Drawing Sheets
